DISHWASHER CONTRAROTARY; SOLUTION RECIRCULATION MEANS AND ATTACHMENTS

Frank Cicero, Los Angeles, Calif.

Application January 15, 1952, Serial No. 266,522

32 Claims. (Cl. 134—96)

My invention relates generally to mechanical washing machines and is concerned more particularly with a machine for washing dishes and is designed to be manually operated, power driven and adaptable to automatic operation. Specifically, the invention pertains to an improved dish washing machine of the general type disclosed in my pending application for patent, Serial No. 117,544, filed September 24, 1949, now abandoned, the present application being a continuation-in-part of said prior application.

It is a general object of my invention to provide a dish-washing machine which is relatively simple in construction, durable in use and highly efficient in thoroughly washing tableware, silverware, glass tumblers, etc. by using minimum amounts of detergents, water and power.

Another object is to provide a dish washer which may be regarded as one of a contra-revolving or dual rotary type, the machine including a tub or receptacle for containing the articles to be washed and the water and the dishwashing or soapy compound or detergent liquid or washing solution and a basket or wire support or carrier on which the dishes and other articles are held, the receptacle and carrier being horizontally revolvable simultaneously in opposite directions during the washing operation. By this provision, the dishes and other articles carried by the basket may be caused to agitate and scoop up the liquids whirling oppositely in the bottom of the tub regardless of the direction of rotation of the basket so that both sides of the dishes are fully subjected to the washing action. A related object is to provide a carrier or wire support having upper resilient arm portions and co-ordinating means making possible for the dishes, set upright, to incline in a direction opposite to the dual rotation of the carrier, the arms being U-shaped and radiating from a tubular hub of the carrier.

Another object is to provide a dish washer of the type indicated in which the tub may be revolved or operated either manually, by means of a suitable operating knob thereon, or by a reversible electric motor connected to rotate a gear operatively connected to the tub at the axis thereof. A related object is to provide gear means for transmitting rotation from the tub to the basket to revolve the latter in reverse direction. This gear transmission means includes a stationary post or support extending upwardly through a tubular hub of the receptacle and provided with an anti-friction bearing, a ring gear secured within the tubular hub and resting upon the bearing to adapt the receptacle to revolve relative to the post, a second ring gear connected within the hub-like central portion of the carrier and positioned above the first-mentioned ring gear, and a plurality of pinions rotatable on axles projecting radially from the stationary post and meshing with both gears, therebetween. By this means, rotation of the receptacle in either direction is communicated to the carrier through the medium of the pinions which function to also rotate the carrier in a direction opposite to that of the tub. If the receptacle is oscillated, the carrier is likewise oscillated, but in opposite directions.

2

Also, by this particular arrangement of gears, the carrier and receptacle may be readily assembled and disassembled from the base of the machine without requiring tightening or loosening of screws, nuts or other elements.

5 Moreover, by this particular arrangement of parts, the carrier merely rests upon the pinions and thus, in the event that the carrier should meet with an obstruction in the bottom of the receptacle, it is free to raise and pass over the obstacle. A related object of the invention is to 10 introduce an improved and substitutive gear transmission means, this includes the aforesaid arrangement but specifically having the ring gears and the pinions respectively of the helical flat type and of the helical cylindric type, both being adaptable to support down and radial thrust while requiring simpler relative assemblage and less driving power.

Another object is to provide a novel and ingenious means for introducing clear, hot water and washing compound into the receptacle, this means including a stationary standpipe having therein a smaller, coaxial tube, the standpipe being connected to a means for forcing the washing compound into the tub through a removable multi-directional perforated cap or spray nozzle or spray head of the standpipe, and the tube being connected to 15 a source of hot and cold water to deliver the same to the interior of the receptacle through said cap, the annular space between the standpipe and the tube normally being closed by a diaphragm. By this construction, clear, hot water, or soapy compound, may be selectively introduced 20 into the receptacle at any time at the discretion of the operator. Another object is to provide an alternative and substitutive carrier or basket, comprising a tubular hub portion from which radiate tangential U-shaped arms in 25 between which the dishes are set inclined, these arms preferably having upper non-resilient portions. Although only one side of the dishes may be subjected to the fullest washing action by the use of this basket, it will serve the purpose satisfactorily since there is yet hot water and dishwashing compound available to spray through the 30 nozzle forcibly against both surfaces of the moving dishes, the carrier being revolvable in both directions.

A further object is to provide means for forcing dish washing compound or detergent into the receptacle, by way of the standpipe. In one of its forms, this injecting 35 means comprises a cylinder for containing a supply of the compound and having an outlet connected to the standpipe, and a hollow or tubular piston or plunger slideable in the cylinder for forcing the fluid therefrom into the standpipe. In this form of the injecting means, the 40 piston is preferably actuated by fluid pressure readily supplied through the same cold water line connecting said tube coaxial to the standpipe. Spring means is provided for returning the piston to first position and a suitable drain pipe serves to discharge the negligible quantity of 45 injected water to allow such return movement of the piston. In another form of the injecting means, a collapsible or resilient container or reservoir is disposed within a suitable casing and is adapted to contain the washing compound, said container being connected to the standpipe. The casing is connected to the cold water line and thus when water is introduced into the casing beneath the container the fluid pressure acts to collapse or squeeze 50 the latter and thereby force the compound therefrom and into the tub, by way of the standpipe.

55 Another important object is to provide means for returning the reusable soapy compound or solution from the tub to the supply cylinder or to the collapsible container. This means comprises a stable circular receiver having a partition dividing the same into an outer annular trough and an inner annular trough, a spout at the bottom of the tube serves to direct the solution from the 60 tub into the outer trough. A return pipe, connected 65

between this trough and said cylinder serves to return the solution from the trough into the cylinder. A check valve within the return pipe allows such return flow of the solution but closes, when subjected to pressure within said pipe, so as to prevent flow of the solution from the cylinder back into said outer trough when the injecting piston is actuated.

A further object is to provide means for draining the washing agents and sediments from the tub upon completion of or during the washing operation. This means includes another spout connected to the bottom of the tub, over the inner annular trough, for directing the liquids and sediments thereinto, a drain tube being connected to this trough for directing them out to waste.

A further object is to provide valves for controlling the return flow of the solution to the cylinder and for effecting drainage of the tub, these valves being disposed within the spouts and adapted to be opened and closed in response to rotation of the tub in either direction. In the present machine, an outer casing encloses the mechanism disposed beneath the tub and the means for operating the valves is mounted on this casing, said means including two circular tracks along which travel rollers carried by valve-actuating arms pivoted adjacent the spouts and connected to the valves. The tracks are provided each with a pair of switch plates operable by control handles or knobs located at the exterior of the casing, these switches serving to transfer the rollers from below a track to up on the same, and vice versa, while the tub revolves in either direction. Vertical movements of the rollers causes the valve actuating arms to pivot so as to open and close the return or recirculation valve and the drain valve of the tub, as controlled by the operator.

A still further object is to provide a desirable means for thoroughly and expediently cleaning glass tumblers and similar articles and of various size. This means, which is a second nozzle or cap and an attachment in the present machine, consists of an expansive tension spring, extended out coaxially from within a tubular member that provides a suitable annular space around said spring, and of a bristly and resilient cloth cap suitably encasing the spring and closing the annular space, said tubular element being provided with a central tubular base whereby this means may substitute the spray nozzle on the standpipe of the tub.

And it is also a general object to provide and show this machine with a clear construction suggesting a further selection of forms and materials, the latter including plastics.

Further objects will appear from the following description, and from the drawings, which are intended for the purpose of illustration only, and in which:

Fig. 1 is a central, vertical, sectional view through my improved dish washing machine;

Fig. 2 is a sectional plan view, taken on line II—II of Fig. 1; and shows in cut sections the radial arms of one of the two carriers; while Fig. 2a shows the tangential arms of the other carrier;

Figs. 3, 4, and 5 are sectional views, taken respectively on lines III—III, IV—IV, V—V, of Fig. 1; Fig. 4 being reduced.

Fig. 6 is a sectional view, taken on line VI—VI of Fig. 3;

Fig. 7 is a vertical sectional view, taken on a line as VII—VII of Fig. 1;

Fig. 8 is a fragmentary front view of the valve control means;

Fig. 9 is a sectional view of the upper end of the standpipe, showing the device applied to use for washing glass tumblers;

Fig. 10 is a plan view of a power means for driving the machine;

Fig. 11 is a sectional-elevation view of the alternative recirculation container for washing solution.

Fig. 12 is an enlarged view taken on line XII—XII of Fig. 1.

Referring to the drawings in detail, my improved dish washing machine includes a large tubular casing 15 having a base flange 16 for supporting the various parts of the machine. Secured to the flange are radial bars 17 which support a vertical tubular post or support 18 about which the tub or receptacle 20 revolves. Welded or otherwise secured to the periphery of the post 18 is the lower race of a ball or roller bearing 21. A flat ring gear 22, having helical teeth radiating horizontally from the periphery of said post, rests upon or is secured to the upper race of this bearing and is secured to the upper end of the hub portion 23 of the tub 20. The tub also has an annular bottom portion 24 and an outer circular wall 25, the upper end of which is provided with an annular ledge 26. The open top of the receptacle 20 is normally closed by means of a lid or cover 30 which is shown as pivoted to the upper rim portion of the tub by means of a suitable hinge 31 but which may be pivoted to the casing 15, if desired. It will be apparent from the foregoing that the tub 20 is freely rotatable on the anti-friction bearing 21 and to effect manual rotation, the cover 30 is provided with a knob 32 adapted to be grasped in a hand of the operator for this purpose. A pin 33 carried by the cover enters a hole in the ledge 26 to key the cover and tub for simultaneous rotation.

A basket or carrier 35 is disposed within the receptacle 20 for supporting dishes and other articles to be washed. The carrier includes a tubular hub 36 and U-shaped arm elements or wire arms 37 connected to and radiating from the hub, preferably at an angle slightly less than ninety degrees. Secured to the upper ends of the outer vertical portions of the arms 37 is a ring 38 which forms the outer upper rim of the carrier. Similar rings 39, 40, 41 secured to the bottom and outer side portions of the carrier provide support for the articles to be washed. To obtain a suitable construction I provide three elongated apertures along the upper end of said tubular hub 36, that is, these apertures are suitably below and parallel to the upper rim of the hub. A figurative length of said apertures is shown by 43, in Fig. 2 and in Fig. 12. I also provide three prongs 44, having a portion slidably circumscribed within the upper end of said tubular hub and contiguous thereto, and having a stud 45 fixed or welded to said slidable portion, said stud being slidable through said elongated apertures, which provide a track for the studs. The non-slidable upper portions of said prongs 44 are bent outwardly and are thus enclosed by welding a tubular ring 46 at the ends thereof to make this ring free to move circularly back and forth, this motion being limited by the elongation of said elongated apertures.

To place the dishes in upright position, or nearly so, light springs 48 are stretched to be resilient between the outer rim of the carrier and the tubular ring 46 in overlying relation to said lower radial portions. Said springs or a portion thereof may also be removable or slidable at either end, or both. Similar springs 49 may extend between the springs 48 and the rings 39 and 40. By adding a ring 47 supported by and spaced outwardly from the hub 36 to beneath the ring 46, compartments are provided wherein silverware and similar articles may be placed upright. Other compartments may also be provided within the carrier.

Without limiting this invention to any particular size or form of the machine, I wish to note that the machine is preferably built in approximately twenty-five inches in diameter, with its carrier preferably comprising twenty-four arms, and that it will satisfactorily wash up to twenty-four large dishes and that many more small ones at a time.

The basket or carrier is supported for rotation within the tub by means to be next described. The upper end of the tubular post 18 is provided with slots 51 in which the inner flattened ends 52 of small axles 53 are disposed,

these axles being screwed into threaded holes in a tubular ring 54 fitted to the upper end of the post, see Figs. 1, 3 and 6, and preferably removably secured to the post. Rotatable on the radially extending axles 53 are, intermediate, cylindric pinions 56 having cylindric-helical teeth meshing with the flat-helical teeth on the ring gear 22. A second flat-helical ring gear 57 is secured to the tubular hub 36 and has helical teeth on its lower surface which mesh with the teeth of the pinions 56. By the construction last described, as the tub or receptacle 20 is rotated, its ring gear 22 acts through the intermediate pinions to rotate the upper ring gear 57 and the carrier 35 connected therewith, in a direction opposite to that of the tub. It is also within the concept of my invention to employ ring gears and intermediate pinions of the bevelled, helical or straight tooth types.

Means are provided for introducing clean water and solution into the tub 20, this means being arranged as best shown in Figs. 1 and 5. Extending through the vertical post 18 is a tube or standpipe 60 having a lower end wall and an open upper end, which is closed by means of a spray nozzle or spray head consisting of an elongated cap 61 provided with multi-directional perforations in its tubular wall. When solution is forced upwardly in the standpipe it discharges through the perforations into the tub upon the articles to be washed. A conical resilient covering 62 surrounds the standpipe beneath the cap 61 and overlies the gear transmission means to protect it against the liquids; the upper inner edge of the ring gear 57 preferably having an annular lip 63 to prevent inward leakage of the liquids. Said yieldable covering thus is also adaptable to absorb exigent shocks effective by said carrier in case of obstruction, such as an object dropped in the bottom of the tub.

The lower end of the standpipe 60 is provided with a lateral branch pipe 64 which is connected to one end of a recirculation cylinder 65 which may be used also as a supply tank. As shown, this cylinder has a reservoir portion 66 of relatively large diameter and an extended end portion 67 of smaller diameter and coaxial to the reservoir portion 66, the end of the portion 66 being closed by a removable end plate 68 provided with a breathing hole. Slidable in the cylinder is a hollow piston 69 having a plate-like head or flange 70 provided with sealing means 71 and a long tubular portion 72 having an inner closed end, which is mounted to be slidable also within end portion 67 in a manner to allow the liquid therein to escape into reservoir portion 66 during the operation. The portion 72 surrounds and is slidable along a tube 73 which is screwed or welded in an axial hole in the end plate 68 and at the other end, which is open, is provided with a sealing 74. Also secured to said hole, exteriorly of the end plate is a manually operable valve 75 which may be of any suitable type. A T joint 76 is joined to the valve 75 and to another valve 77 and may be connected to a cold water supply line of the house or establishment. Assuming that there is liquid dishwashing compound or solution in the cylinder, when water under pressure is introduced into the tube 73, and thus into the tubular portion 72 of the piston 69, the latter is forced toward the left as viewed in Figs. 1 and 5 to force solution from within the cylinder upwardly into the standpipe 60 by way of the pipe 64. When the water pressure is discontinued, as by closing the valve 75, a tension spring 80, not shown in Fig. 1 and shown in Fig. 5, connected between the inner end of the tubular portion of the piston, and therewithin, and the end plate or thereabout, acts to return the piston to first position. During this action, the water used for the actuation is cleared from the interior of the piston and of the tube through a discharge pipe 81, connected to a drain pipe 82, to be later described. Pipe 81 must have a much smaller passage of flow than tube 73. As will be more fully explained, the solution flows from the tub 20, whereto is originally supplied, into the cylinder 65 and is returned to the tub

5 by way of the standpipe 60. The branch pipe 83 of the lower end of a tube 84 is held or welded in the lower end of the standpipe, the two being coaxial. The branch 83 communicates with a branch pipe 85, which is connected to the valve 77, and communicates with a hot water supply line 86 which may be connected to the supply of hot water of the house and provided with a valve adjacent the valves 75 and 77 for an easier operation. By this arrangement it is possible to inject hot and cold water in the tube 84 expediently. The upper end of the tube 84, which is located below the cap 61, carries a resilient washer or baffle 87 which normally engages the interior wall of the standpipe 60 to prevent the water passing upwardly through the tube 84 into the cap 61 from flowing downwardly in the standpipe. When solution is forced upwardly in the standpipe through apertures provided on the outer rim of a washer 88 carried by the tube 84 beneath the baffle 87 to hold the same in place and concentric to the standpipe 60, this baffle yields to permit such flow; said baffle being supported preferably by an incision on said tube. The tubular hub portion 23 of the tub 20 is provided with a plurality of overflow holes 88 through which excess liquids in the bottom of the tub can flow outwardly to maintain them at a pre-determined level within the tub. The exterior bottom of the tub beneath the hub may be provided with an annular lip 89 to guide said overflow into the inner section of the member 91, to be next described.

30 Supported by legs 90 which are secured to the flange 16 is a stable pan-like annular member 91 which has a central tubular portion 92 extended up to within the hub 23 at a point above the overflow holes. The member 91 also has a bottom wall 93 and an upstanding peripheral rim 94. A circular partition 95 divides concentrically the member 91 into an inner, annular waste drain trough 96 and an outer, annular solution return trough 97. The drain pipe 82 is connected to the bottom of the trough 96, which is adapted to receive the liquids to be drained from the tub 20, said liquids discharging from the tub through a spout 98 and through the overflow holes 88. A valve element 100 is adapted to engage a seat within the spout 98 to normally close the latter and thus retain the liquids within the tub, the valve element being carried by an arm 101 vertically pivoted, by the aid of any suitable means, to the spout at 102, said spout being provided with an aperture to allow the vertical motion of said arm. Another spout 105 is aligned with and adapted to convey reusable solution from the tub into the trough 97, a suitable valve element 106 being provided for controlling this flow. The element 106 is carried by an arm 108 pivoted at 109.

40 Baffles 110 and 111 are provided within the tub on its bottom for directing the liquids into the spouts and also for deviating said liquids upwardly during the operation. Additional similar baffles may be provided. The bottom wall of the tub may be perforated as indicated at 112 for straining sediments from the solution flowing from the tub and, to aid the percolation of said solution into the spout, it is wise to secure a brush on the bottom of the carrier in a manner that it will keep the bottom of the tub clear of sediments during operation at a radius over said perforations. Similar brushes may be provided wherever desired.

45 55 60 65 70 75 A casing 113 of a check valve is secured to an aperture at the bottom of the trough 97 and in fluid communication with a pipe 114, this being connected to the interior of the cylinder 65 for conveying the solution from the tub to the recirculating cylinder 65. Said valve having an axially movable disc 115, preferably of fibre, therein provided for automatically closing the pipe 114 when pressure, hydro or pneumatic, is developed therein during actuation of the piston 72, the check valve thus preventing back flow of the liquid into the trough 97. As shown in Fig. 1, the disc 115 normally rests, or is supported by pins provided within a tubular member

116 of the valve, this member having apertures above said resting disc, or clear of said disc, and having a flared lower portion or bottom also having aperture and preferably at the rim. Said member 116, which is surrounded by the casing 113, thus closes the same with its flared bottom. The straight top portion of this member 116 abuts at a firm washer-like cap 117, that closes the casing and has a central hole engageable by the disc 115 to close it and close, therefore, the pipe 114, as explained above. The liquid first flows in through said central hole and out through the smaller adjacent holes and then into the pipe 114 through the holes on the flared rim. So constructed this valve gives perfect and perennial performance.

The valves 100 and 106 are actuated by tilting the respective arms 101 and 108, such tilting action being effected mainly by means of two circular tracks 120 and 121, provided on the interior of the casing 15 and extending therearound. The outer end of the arm 101 has a roller 125 which normally is maintained and travels below the lower track 121, by means of a flat steel spring 126 that forces the arm downwardly to retain the valve 100 closed. The roller 125 is, however, caused to be raised onto the top of the lower track 121 to tilt the arm 101 in a direction to open the valve 100. This action is accomplished by means of switch plates 128 and 129 which, as shown in Fig. 7, are pivoted on the track 121 and normally held in the plane thereof by the aid of flat steel springs 130 provided beneath the track to engage said plates, or by the aid of similar means provided on the outer surface of the casing 15 to keep horizontal the knobs or handles 133 and 134, Fig. 8, and the relative switch plates 128 and 129. The pivot pins 132 carrying the switch plates extend through the casing and have the knobs connected to their outer ends. When either of the handles 133 and 134 is pivoted downwardly, as indicated by the curved arrows, the switch plate 128 or 129, as the case may be, is tilted downwardly, thus providing an inclined ramp along which the roller 125 is caused to roll upwardly onto the top of the track 121 when the tub 20 is revolving in either direction. As indicated by the horizontal arrows in Fig. 8, when the tub is revolving toward the right the handle 133 is operated and when rotation of the tub is toward the left, the handle 134 is operated. Thus, by shifting the roller from below the track 121 upwardly onto the top of the same, the arm 101 is pivoted to open the drain valve 100. To again close the valve 100, the handle 133 or 134, depending upon the direction of rotation of the tub, is pivoted downwardly, contrary to as explained above for opening the valve, to cause the switch plate 128 to 129 to act as a ramp along which the roller 125 rolls downwardly below the track 121 to close the valve 100. Should the operator pivot the wrong knob, a click caused by the roller would serve as a quick notice. The operator should let the washer make a complete rotation before let go of the knob, which automatically returns to first position.

Another roller 136 at the end of the arm 108 normally is maintained and travels below the track 120 to keep the detergents valve 106 closed. However, the roller 136 is adapted to be raised onto the top of the track 120 by either of two switch plates 137 and 138, the pivot pins 132 carrying the plates and handles 140 and 141, Fig. 8. By operating these handles, the switch plates may be tilted to cause the roller to ride up onto the top of track 120 and to allow return of the roller to below the same, so as to open and close the valve 106.

While the tub or receptacle 20 may be rotated manually by means of the knob 32, it is within the concept of this invention to provide means for power-operating the washer. As shown in Fig. 1, a tubular driving element or shaft 145 may be located between the post 18 and the hub 92 of the member 91, the upper end of this element being welded or otherwise joined either to the

lower gear 22 or to the hub 23, or to both. At its lower end, the driving elements carries a bevel gear 146 which may be rotated by any suitable prime mover, such as the pinion 147 of the reversible electric motor 148, shown in Fig. 10, which may easily be mounted within the casing 15, below the tub. A suitable bearing 149 contiguous the post and the element 145 may be provided.

The operation of my improved dish washing machine should be apparent from the foregoing description and for this reason only a brief outline of the operation will now be given. To prepare the machine for washing, the articles are placed within the basket or holder 35, after which the cover 30 is closed. By connecting the pipe 86 to the supply of clean, hot water, this is caused to flow upwardly through the tube 84 and the cap 61, thence into the tub 20 through the multi-directional perforations in the cap. The hot water, which thus is sprayed against the articles, produces a rinsing or pre-washing operation. At this stage the valve 106 remains closed and the valve 100 may be kept open while the washer should be oscillated. Should an excessive amount of liquids be present at any time in the tub, the excess will drain out through the overflow holes 88 into the trough 96 and thence to waste.

The tub 20 is revolved, either manually or by power applied by the motor 148. As the tub and carrier are revolved contrarily to each other, the liquid on the bottom of the tub is swirled in one direction while the articles in the carrier are moved in the opposite direction to cause their lower portions to scoop up the agitated liquid. By rotating the tub first in one direction and then in the opposite, both sides of the articles are eventually thoroughly washed. This being accomplished as follows. The carrier, having resilient upper arm portions connected to the circularly oscillatable ring 46 and this oscillation being equi-limited in both directions within the width of the elongated apertures on the hub 36, the dishes being vertically placed through the resilient portions of the arms and resting on the rings 39 and 40 and said dishes thus having the lower portion of the rims extended beneath said rings 39 and 40 and so being barred from sliding motion by the adjacent arms, but being conformingly free to slide radially to the axis of the carrier. When the carrier is revolved relatively fast in either direction, the lateral force, that is the impact of the air, effected upon the plane of the dishes will cause them to fall or incline to the opposite direction, since only the upper portions of the carrier are resilient and the lower portion of the rim of the dishes is properly locked. The center section or portion of Fig. 2 shows the radial resilient arms 48 in a tangential position as if they were forced by the lateral force of the dishes in rotation. Moreover, this inclination of the dishes and the respective radial slide will function to oscillate the tubular ring 46 also in the opposite direction of the rotation of the carrier, thus to suitably swing the resilient portions of the arms in a position tangent, or nearly so, to the periphery of said ring 46; this motion conforming with the said radial slide of the dishes, the resilient portion of the arms providing the stretch required for the inclination of the dishes. And so is obtained the required dual radial inclination for a very desirable performance of a machine of the type indicated. The washing compound or clean solution is supplied in the present machine by pouring it into the tub 20 wherefrom is drained into the cylinder 65 by operating either recirculation knobs 140—141 to open the spout 105. An extra tank for the purpose of containing a supply of the clean detergent may easily be connected to the cylinder or the latter may be used for the sole purpose of containing said supply. To inject washing solution into the tub, once both valves are closed, and go on with the main washing operation, the operator then opens the valve 75 to build up water pressure which causes the solution to move from within the cylinder upwardly through the

standpipe 60 and thence upon the dishes and other articles therein. After the main operation, the operator may cause the solution to return to the cylinder by simply operating the appropriate control knob 140 or 141, the particular one depending upon the direction of rotation of the tub. This knob causes one of the switch plates 137 or 138 to pivot downwardly so as to provide a ramp along which the roller 136 of the valve arm 108 travels to tilt the arm and open the valve 106. After the final rinsing operation with clear, hot water, and this being drained out by operating either of the knobs 133 or 134 in the same manner as for the other knobs, the lid of the tub should be left open to allow the articles just washed to dry up while the washer should be kept revolving.

My dish washing machine, however, may be operated in any selected sequence, at the discretion of the operator. That is, any desired number of washing and rinsing operations may be performed in any desired order and this is an important consideration since the number and duration of such steps depends largely upon the condition of the dishes and other articles prior to washing.

A very important feature resides in the means by which the washing solution may be re-used as often as desired, the invention providing simple and efficient means for recirculating the solution to and from the tub, and for storing it in the supply cylinder for later use. Moreover, by arranging the supporting means of the carrier so that they hold the dishes inclinable to either direction, an improved washing action is produced and the articles are thoroughly cleaned. Since it is within the concept of this invention to provide the machine with an alternative and substitutive carrier or basket, I believe a related brief description is sufficient because this carrier has the same general construction of the one already described. However, it does differ in what follows and has the lower or bottom portions of the U-shaped arms 37 radiating tangentially, or nearly so, from tubular hub 36 and are visible in Fig. 2^a only in between the hub 36 and the ring 47' as indicated by 37'. The upper portions of the arms 48' are also radiating tangentially, or nearly so, from a ring 47' which is same as the ring 47 and is secured to the upper end of the tubular hub 36 and thus replacing the slideable ring 46, the lower and lateral portions of the arms, the ring and the tubular hub being compact. The upper portions of the arms, or a number of them, are preferably slideable or detachable.

My invention also contemplates means for brushing and rinsing glasses, cups, etc. Referring to Fig. 9, this means, which is the second nozzle previously mentioned, consists of a compression or tension spring 165, having a long so-called music wire spring 166 surrounding its coils, extended upright from within a large tubular member 167 coaxially thereof. Said large member has a turned-in portion on one end, or bottom, to form a shoulder 168 and thence is carried outwardly by a small tubular member 169, wherein the spring 165 may be secured, said member 169 being adaptable on or over the top of the standpipe 60 after removing the perforated cap therefrom. Thus, said large member is adaptable to be in fluid communication with said standpipe and it provides a depth and a width wherein glasses of various size may be inserted over the expansive spring 165, this being of a length that accommodates insertion of glasses of various depth. The large tubular member may well be made of resilient material which also facilitates insertion thereinto of deep cups with handles, eliminating therefore the need of an ordinary U-slot at the upper end of said member. The large tubular member is further provided with a folded-in edge to form a circular open hem 170, at the other end, whereat is provided with several small holes or apertures 171 preferably of dual direction adaptable to direct liquids, trapped within said hem, respectively toward the periphery of the expansive

spring and over the top or outer end of the same. In this manner it is possible to spray the liquids around the outside of a glass 173, held by hand for motion over the spring 165, and apically over this spring to also provide a further fountain-like rinsing source of liquids. Right below, or adjacent the small holes many other holes 174 are provided horizontally through the doubled edge of the member 167. A collapsible, or resilient, excretory cap 175, preferably made of elastic cloth tapped or bristly woven, encases the expansive spring and has one end portion 176 flared, the edge of which is sewed tightly to said horizontal holes 174, so preventing any amassed escape of fluid from within. Said cap is sewed also on the spring 165 at a point intermediate the ends of the member 167 and a space is provided in between the reversed portion 176 and the shoulder 168 in order that deeper glass may freely be pushed down in far enough to allow the top of the capped spring to abut on the bottom of said glass.

Moreover, the music wire spring 166, wound through the coils of the spring 165 provides a soft and expansive peripheral wall; the increase of the water pressure will cause also further expansion of the cap. This fact makes possible to scrub thoroughly also the inside of larger glasses or cups by the use of this single device. And, of course, it is not to disregard the fact that the outer portion of the glass will also be subject to a thorough scrubbing action, since it will be wrapped up or surrounded by the fluid emanating teasels or bristles of the reversed portion of the cap.

Referring to Fig. 11 my invention further contemplates an alternative means for injecting the washing solution into the tub 20. This means includes a housing 152 preferably slightly conical, with the large base at the bottom, having an inlet port 153 which is connected to the cold water valve 75 by means of a pipe 154 which is provided with a discharge pipe, same as the discharge pipe 81 for the cylinder 65, however, not shown in Fig. 11. Arranged within the housing is a bag-like collapsible, or resilient container 155 provided with two mouths 156 and 157. The mouth 156 is connected to the lower end of a pipe 158 by means of a clamp ring 159, said pipe leading to the trough 97 and taking place of the pipe 114. The other mouth 157 is connected to the lower end of a pipe 160 by means of a clamp ring 161 said pipe extending to the standpipe 60 and taking place of the pipe 64.

Assuming that there is washing solution within the container 155, to inject this solution into the tub 20, by way of the standpipe, pressure or water under pressure is introduced into the housing 152 and this acts to compress the container. Thus, the washing solution is displaced, through the pipe 160 into the standpipe. At this time, the check valve of the pipe 114 remains closed as previously explained. To return the solution to the container for recirculation, the valve 106 is opened to allow flow of the solution from the tub 20 into the trough 97, wherefrom it flows into the container by way of the line 158. Assuming that one wants to displace only a portion of said solution, then that is simply done by shutting off the pressure or control valve.

The washing machine as above described may be regarded as one of a manual type. However the structure disclosed lends itself to fully automatic operation. For example, the tub and carrier or basket may be power driven first in one direction and then in the opposite one and the duration of rotation in either direction may be controlled by a suitable timing device. Preferably such a timing device will open and close the valves and control the injection of the clear water in a predetermined order to perform the desired operation. It can yet control the opening of the lid 30 and the keeping on the rotation until the washed dishes will quickly dry up and cool off, said lid being pivoted to the casing 15, if desired.

While I have herein shown my washing machine as

11

embodied in several forms of construction, by way of example, it will be apparent that further alterations or modifications might be made in the construction without departing from the spirit of the invention. Consequently, without limiting myself in this respect, I claim as my invention:

1. A machine of the type referred to, including: a rotatable tub for containing liquids, a driving connection for said tub being mounted coaxially thereto on a tubular support and said tub having an upwardly extended tubular hub surrounding said support; inlet means mounted through said tubular support and adaptable to inject liquid into the tub during and off rotation; a spout and valve thereof connected to the bottom of the tub adjacent the hub and adaptable to eject the drainage from within the tub during and off its rotation; and a stable annular receiver mounted below and vertically aligned with said spout for disposing of said drainage during and off said rotation.

2. A machine as defined in claim 1 and including: a standpipe surrounding said inlet means and through which washing solution may flow; fluid pressure actuated means for forcing the solution through the standpipe; a second spout and valve adaptable to eject the solution from within the tub during and off its rotation; and a second receiver mounted contiguous to said drainage receiver for disposing of the solution flowing from the tub into said pressure-actuated means, thus to make possible a recirculation of the solution.

3. A machine of the type referred to including: a rotatable tub for containing liquids, a driving connection for said tub being mounted coaxially thereto on a tubular support and said tub having an upwardly extended tubular hub surrounding said support; a spout and a valve thereof connected to the bottom of the tub adjacent the hub and adaptable to eject the drainage from within the tub during and off its rotation; and a stable annular receiver mounted below and vertically aligned with said spout for disposing of said drainage during and off said rotation.

4. A dish washing machine, including: a tub mounted for horizontal rotation in either direction; a carrier rotatable coaxially within the tub and adapted to support articles to be washed; an upright post; and a driving connection between said tub and said carrier by which rotation of the tub in either direction effects simultaneous rotation of the carrier in a direction opposite to that of the hub, said driving connection comprising an anti-friction bearing surrounding said post and secured thereto, a first ring gear carried by said tub coaxially thereof and supported by said bearing, a second ring gear carried by said carrier coaxially of said first ring gear, a plurality of axle pins carried by and projecting radially from said post, and a pinion rotatable on each of said pins and disposed between said ring gears and meshing therewith.

5. A machine as defined in claim 4 in which said ring gears have flat teeth deviating helically from the center of the axis of rotation of said ring gears, and in which said pinions meshing with said ring gears have cylindrical helical teeth of long lead.

6. A dish washing machine, including: a tub mounted for horizontal rotation in either direction; a carrier rotatable coaxially within the tub and adapted to support articles to be washed; a stable upright post; and a driving connection between said tub and said carrier by which rotation of the tub in either direction effects simultaneous rotation of the carrier in a direction opposite to that of the tub, said driving connection comprising a tubular hub extending up from the bottom of said tub, a tubular hub extending up from the bottom of said carrier, an anti-friction bearing surrounding said post and secured thereto, a first ring gear carried by said tub coaxially thereof and resting upon said bearing, a second ring gear carried by said carrier and coaxial with said first ring gear, a ring surrounding said post adjacent the upper end thereof, slots provided in the upper end of said post, a plurality

5

of axle pins each having a threaded portion screwed into a threaded hole in said ring, a flattened end disposed in a said slot and an enlargement at its other end, said pins projecting radially from the post; and a plurality of pinions rotatable on said pins, said pinions being disposed between said ring gears and meshing therewith.

7. A dish washing machine, including: a tub mounted for horizontal rotation in either direction; a carrier rotatable coaxially within the tub and adapted to support articles to be washed; and a driving connection between said tub and said carrier by which rotation of the tub in either direction effects simultaneous rotation of the carrier in a direction opposite to that of the tub, said driving connection comprising a rotary support, a first ring gear carried by said tub coaxially thereof and resting upon said support, a second ring gear carried by said carrier coaxially of said first ring gear, and a plurality of pinions rotatable on fixed axles extending radially from the axis of rotation of said ring gears, said pinions being disposed between and meshing with the ring gears, rotation of said first ring gear being transmitted by said pinions to said second ring gear to cause the latter to rotate in the direction opposite to that of the first ring gear.

20 8. A machine as defined in claim 7 and including: a tubular shaft secured rotatively with said tub and coaxial thereof, said shaft surrounding said rotary support; a ring gear on the lower end of said shaft; and a prime mover having a pinion meshing with said gear, operation of said prime mover effecting rotation of said tub.

9. A machine as defined in claim 7 in which said carrier, being adaptable to swing the dishes therein in dual radial inclination, comprises: a vertical tubular hub supported by said second ring gear and depending within said tub; a ring carried by the upper end of said hub and thereat circularly oscillatable, said ring having strut means connected to the hub and track means being provided on the hub for the strut means; arm members having horizontal portions projecting radially from the lower end of said hub and having vertical portions upwardly at their outer ends; rings joining all of said horizontal and said vertical portions and a number of them serving as supports for the dishes to be washed; resilient members connecting the upper end of said vertical portions and said oscillatable ring in overlying relation to said radial portions, said resilient members being adaptable to take a position tangential to the periphery of said oscillatable ring, this being adaptable to oscillate contrarily to the dual rotation of said carrier due to the lateral force or impact effected upon the plane of dishes placed in upright position in between said arms of said carrier during relatively fast rotation of the latter.

10. A machine as defined in claim 7 in which said carrier, being adaptable to swing the dishes in dual radial inclination, comprises: a vertical tubular hub supported by said second ring gear and depending within said tub; a number of elongated apertures along the upper end of said hub; a ring surrounding coaxially said upper end of the hub, the former being of larger diameter than the latter, and having; a number of prongs with the end slidably secured through said elongated apertures so that the ring may be circularly oscillated; arm members having horizontal portions projecting radially from the lower end of said hub and having vertical portions at their outer ends; rings joining said horizontal and said vertical portions and serving as supports for the articles to be washed; resilient members connecting the upper end of said vertical portions and the oscillatable ring in overlying relation to said radial portions, said resilient members being adaptable to take a position tangential to the periphery of said oscillatable ring, this being adaptable to oscillate contrarily to the dual rotation of said carrier due to the lateral force or impact effected upon the plane of dishes placed in upright position in between said arms of said carrier during relatively fast rotation of the latter; and

75

a second ring fixed coaxially to the lower portion of said tubular hub for providing a further support for silverware that may be placed upright through the annular space provided between the hub and the surrounding rings.

11. A machine as defined in claim 7 and including means for introducing washing solution into said rotatable tub, said means comprising: a standpipe extending upwardly through said rotary support and through which the solution may flow; a multi-directional perforated cap detachably secured to the upper end of the standpipe; and fluid pressure actuated means for forcing the solution upwardly, through said standpipe, to cause it to pass through the perforations of said cap.

12. A machine as defined in claim 7 and including means for introducing washing solution into said rotatable tub, said means including: a standpipe extending upwardly through a tubular member of said rotary support and through which the solution may flow; a multi-directional perforated cap detachably secured to the upper end of the standpipe; and fluid-actuated means for forcing the solution upwardly, through said standpipe, to cause it to pass through the perforations of said cap, said fluid-actuated means comprising a cylinder for containing the solution and in fluid communication with the interior of said standpipe; a fluid-pressure-actuated hollow piston slideable in said cylinder and adapted, when slid in one direction, to force any quantity of the solution from the cylinder into said standpipe; spring means within said piston normally sliding the same in the opposite direction; and means for discharging said fluid used for the actuation from within said piston.

13. A machine as defined in claim 7 in which said carrier comprises: a vertical, tubular hub carried by said second ring gear and depending therefrom within said tub; U-shaped arm members, each having the ends projecting respectively from the top and from the bottom of the tubular hub tangentially thereto and substantially horizontally; and means connecting respectively the lower and the vertical or outer portions of the arms.

14. A machine as defined in claim 13 in which said connecting means partly comprise rings firmly resting on the bottom of the carrier and spaced intermediate its peripheries for supporting the dishes set upright between the upper and the lower portions of the arm members and for permitting the lower edge of the dishes to depend from the bottom of the carrier thus to scoop up the low-level surface of the liquid in the tub, beneath the carrier, during the rotation of the same.

15. A machine as defined in claim 7 and including means for introducing washing solution into said tub, said means including: a standpipe extending upwardly through a tubular member of said rotary support and through which the solution may flow; a multi-directional perforated cap detachably secured to the upper end of the standpipe; and fluid-pressure-actuated means for forcing the solution upwardly, through said standpipe, to cause it to pass through the perforation of said cap, said fluid-actuated means comprising a cylinder for containing the solution and in fluid communication with the interior of said standpipe; a fluid-pressure-actuated hollow piston slideable in said cylinder and adapted, when slid in one direction, to force any quantity of the solution from the cylinder into said standpipe; and spring means adaptable to slide automatically the piston in the opposite direction, said machine further having means for returning said washing solution from the tube to said cylinder, said solution returning means including a spout at the bottom of the tub; an annular stable trough adaptable to funnel said solution flowing from said spout to within said cylinder; and a return pipe communicating with the interiors of said trough and of said cylinder.

16. A machine as defined in claim 15 in which said solution returning means also includes a normally closed valve in said spout for retaining the solution within the

tub; and control means operative to open and close said valve.

17. A machine as defined in claim 15 in which said solution returning means includes a normally closed valve in said spout for retaining the solution within the tub; and control means for said valve operative in response to dual rotation of said tub for opening and closing said valve, said control means including an arm vertically pivoted adjacent said spout and carrying said valve on one end; a roller provided on the other end of said arm; a cylindrical casing that encloses all the machinery parts below said tub; a circular track below which said roller normally may travel, said track being provided by said casing; a pair of switch plates pivotable on said track and forming a portion thereof to serve as ramp to cause said roller to ride up on the track, in order to tilt said arm to pivot said valve open, and to ride down to travel below said track in order to cause the closing of said valve; spring means aiding the pivoting of said arm and tending to hold said roller of said arm below said track, thus to keep said valve closed; handle means carrying said switch plates from the outside of said casing and by which said plates are pivotable, this pivoting causing the opening and closing of the valve, this being effected dependently of the direction of rotation of said tub and of the pivoting of the respective handle of said handle means; and spring means tending to hold said switch plates and respective handles unpivoted.

18. A machine as defined in claim 17 and including: a separate spout at the bottom of the tub adaptable to drain waste liquids; a separate stable annular trough surrounding said tubular member of said rotary support and being adaptable to funnel the waste liquids and overflow of the tub; and means duplicating said solution return control means adaptable to control said drainage of waste liquids.

19. A machine of the type referred to including: a tub having an inlet and an outlet through which washing solution can be respectively introduced into and discharged from the tub; a cylinder for containing the solution and in fluid communication with the interior of the tub, said cylinder having a coaxial, reduced, extended portion at one end; a tube, in fluid communication with a source of water under pressure, mounted at the end opposite to said reduced portion and extended coaxial to and within the cylinder; a fluid-actuated hollow piston having one open end provided with a relatively large flange, the piston enclosing and normally surrounding the tube and being adaptable to slide freely to and from said extended portion, while permitting movement of the solution therefrom, and being adapted when slid into said extended portion to force any quantity of the solution from the cylinder into the tub; spring means secured within the tube and adaptable to move the piston to the idle or first position for making space in the cylinder available for reusable solution or a new supply of the same, sealing means within the piston and around the tube and means discharging pressure from within said piston being provided, the latter means comprising a discharge pipe connected to the tube outwardly of the cylinder.

20. A machine of the type referred to comprising: a tub for containing liquids and articles; outlet means for said liquids; means for introducing washing solution into said tub, said means including: a standpipe through which the solution may flow; a multi-directional perforated cap detachably secured to the upper end of the standpipe; and fluid-pressure-actuated means for forcing the solution upwardly through said standpipe to cause it to pass through the perforations of said cap, said pressure-actuated means comprising a cylinder for containing the solution and in fluid communication with the interior of said standpipe; a fluid-pressure-actuated hollow piston slideable in said cylinder and adapted, when slid in one direction, to force any quantity of the solution from the cylinder into said standpipe; and means whereby said fluid used for the actuation is discharged from within said piston.

21. A machine of the type referred to, including: a rotatable tub having an inlet and an outlet through which washing solution can be respectively introduced into and discharged from the tub; a cylinder adapted to contain a supply of the solution; a first fluid line connected between the interior of said cylinder and said inlet of the tub; a second fluid line extending between said outlet of the tub and the interior of the cylinder; a piston slidable within said cylinder in a first direction, to force the solution or any quantity thereof from the cylinder through said first fluid line into said tub, and slidable in the opposite direction to provide a space for receiving washing solution discharged from the tub through said second fluid line; and valve means in said outlet, said valve mean being normally closed to retain the solution within the tub but adapted to be opened to allow discharge of the solution through said outlet.

22. A machine of the type referred to, including: a tub having an inlet and an outlet through which washing solution can be respectively introduced into and discharged from the tub; a closed housing; an inlet for introducing fluid under pressure into said housing and for discharging the same; a bag-like, collapsible receptacle adaptable to contain said solution; disposed within the housing and having an inlet neck and an outlet neck projecting from the housing; a first fluid line extending between said outlet neck and said inlet of said tub; a second fluid line extending between said outlet of the tub and said inlet neck, pressure fluid introduced into said housing collapsing said receptacle to force the washing solution through said first line into the tub, the solution being adapted to return from said tub to said receptacle through said second line when said fluid pressure is relieved; and valve means being normally closed to retain the solution within the tub but adapted to be opened to allow discharge of the solution through said second line.

23. A machine as defined in claim 22 in which said second fluid line comprises an annular stable trough adaptable to funnel the solution flowing from said outlet of the tub to the interior of said receptacle, this also being stable and said tub being rotatable; and a check-valve allowing flow of the solution from said trough into said receptacle and preventing back flow of said solution into said trough.

24. A machine of the type referred to, including: a rotatable tub having an inlet and an outlet through which washing solution can be respectively introduced into and discharged from the tub; a cylinder adapted to contain a supply of the solution; a first fluid line connected between the interior of said cylinder and said inlet of the tub; a second fluid line extending between said outlet of the tub and the interior of said cylinder, said second fluid line including an annular stable trough adaptable to funnel said solution flowing from said outlet of the rotatable tub to the interior of said cylinder, this also being stable; a piston slidable within said cylinder in a first direction to force solution therefrom into said tub, and in the opposite direction to provide space for receiving reusable washing solution discharged from said tub through said second fluid line; valve means in said outlet, said valve means being normally closed to retain the solution within the tub but adapted to be opened to allow discharge of the solution through said outlet; and a check valve in said second line allowing flow of the solution from said trough into said cylinder but preventing back-flow of said solution into said trough.

25. A machine of the type referred to including: a tub revolvable in two directions; a cover for said tub; a carrier revolvable within said tub and coaxial therewith; a contra-rotary gear drive between said tub and carrier; a tubular vertical post supporting said tub and carrier; a standpipe extending through said post into said tub; nozzle means provided alternative in the present machine at the upper end of said standpipe, thus being effectual of back-pressure therein; means for forcing washing solution

upwardly through said standpipe into the tub by way of said nozzle means; a tube extending coaxially through said standpipe for directing clear water into said nozzle means; a yieldable baffle carried by said tube and normally closing the annular space between the tube and the standpipe to prevent said compressed water from flowing downwardly through the standpipe, said baffle flexing to allow flow of the solution upwardly through the standpipe; a washer-like means to hold in place said tube and to support said baffle; this means permitting flow of the solution adjacently the inner wall of said standpipe; and a covering secured beneath said nozzle means to protect said gear drive and to be adaptable to absorb exigent shocks.

26. A machine of the type referred to comprising: a receptacle for liquids and articles to be washed; a pipe extending into said receptacle; a nozzle means provided at the end of said pipe, thus being effectual of back-pressure therein; means for forcing washing solution through said pipe into the receptacle by way of said nozzle means; a tube extending coaxially through said pipe for directing clear water into said receptacle; a yieldable baffle carried by said tube and normally closing the annular space between the tube and the pipe to prevent said water from flowing backwardly through the pipe, said baffle flexing to allow flow of the solution outwardly through the pipe; and means to hold in place said tube and to support said baffle, this means permitting flow of the solution adjacently the inner wall of said pipe.

27. A dishwashing arrangement comprising: a receptacle for liquids and articles to be washed; a pipe extending into said receptacle; a means for cleaning glass tumblers; means for forcing washing solution through said pipe into the receptacle by way of said means for cleaning glass tumblers; a tube extending coaxially through said pipe for directing clear water into said receptacle; a yieldable baffle carried by said tube and normally closing the annular space between the tube and the pipe to prevent said water from flowing backwardly through the pipe,

40 said baffle flexing to allow flow of the solution outwardly through the pipe; and means to hold in place said tube and to support said baffle, this means permitting flow of the solution adjacently the inner wall of said pipe, said means for cleaning glass tumblers comprising: a tension spring; a large tubular member provided with a turned-in shoulder; a small tubular member for supporting said shoulder and the spring and for adaptation over the end of said pipe; an excretory cap encasing the spring and suitably closing an annular space provided around a portion of the spring by the large tubular member; excretory, collapsible means for surrounding the outer periphery of a glass that may be inserted over said capped spring; and means for spraying said outer periphery and adjacently thereof, said spraying means including an open hem on the rim of the large tubular member and said hem being provided with plural-direction apertures which are adaptable also to direct liquid apically over said cap.

28. A machine as defined in claim 27 in which said means for forcing washing solution includes a reservoir for said solution and including a fluid line communicating the interior of the tub with the interior of the reservoir, said line being adaptable to direct the used solution from the tub into the reservoir for permitting the reinjection or recirculation of said solution through said means for cleaning glass tumblers.

29. A machine as defined in claim 27 and including a music wire spring surrounding the coils of said tension spring for making the latter expansive and adapt therefore to insert into glass tumblers of various size, said excretory cap being made of elastic material and increased fluid pressure within said cap causing further expansion of the same.

30. A machine of the type referred to comprising a rotatable tub for containing liquids; a driving connection by which the tub may be rotated in either direction; a

spout connected to the bottom of the tub; a normally closed valve in the spout for retaining the liquids within the tub; and control means for said valve operative in response to dual rotation of said tub for opening and closing said valve, said control means including an arm vertically pivoted adjacent said spout and carrying said valve on one end; a roller provided on the other end of said arm; a cylindrical casing that encloses all the machinery parts below said tub; a circular track below which said roller normally may travel, said track being provided by said casing; a pair of switch plates pivotable on said track and forming a portion thereof to serve as ramp to cause said roller to ride up on the track, in order to tilt said arm to pivot said valve open, and to ride down to travel below said track in order to cause the closing of said valve; spring means aiding the pivoting of said arm and tending to hold said roller of said arm below said track, thus to keep said valve closed; handle means carrying said switch plates from the outside of said casing and by which said plates are pivotable, this pivoting causing the opening and closing the of the valve, this being effected dependently of the direction of rotation of said tub and of the pivoting of the respective handle of said handle means; and spring means tending to hold said switch plates and respective handles unpivoted.

31. A machine of the type referred to comprising: a tub having an inlet and an outlet through which washing solution can be respectively introduced into and discharged from the tub; a fluid-pressure-activated reservoir adapted to contain a supply of the solution; a first fluid line connected between the interior of the reservoir and the inlet of the tub; a second fluid line extended between the outlet of the tub and the interior of the reservoir; means adaptable to provide space in the reservoir for receiving re-usable solution discharged from the tub through

the second fluid line; and a check valve in said second line allowing flow of the solution into the reservoir but preventing back flow therethrough of the solution when the latter is being pressure-ejected through the first fluid line from the cylinder.

32. An arrangement for washing tableware comprising: a receptacle for liquids; a pipe in fluid communication with liquid or liquids under pressure and extending into said receptacle; and a means for cleaning glass tumblers provided at the end of said pipe, said means comprising: a tension spring; a large tubular member provided with a turned-in shoulder; a small tubular member for supporting said shoulder and the spring and for adaptation over the end of said pipe; an excretory cap encasing the spring and suitably closing an annular space proved around a portion of the spring by the large tubular member; excretory, collapsible means for surrounding the outer periphery of a glass that may be inserted over said capped spring; and means for spraying said outer periphery and adjacently thereof, said spraying means including an open hem on the rim of the large tubular member and said hem being provided with plural-direction apertures which are adaptable also to direct liquid apically over said cap.
